US00D985415S

(12) **United States Design Patent** (10) **Patent No.:** **US D985,415 S**
Raftis (45) **Date of Patent:** **** May 9, 2023**

(54) **PENDANT**(71) Applicant: **Nicholas Dennis Raftis**, Alvin, TX
(US)(72) Inventor: **Nicholas Dennis Raftis**, Alvin, TX
(US)(**) Term: **15 Years**(21) Appl. No.: **29/836,991**(22) Filed: **Apr. 29, 2022****Related U.S. Application Data**

(62) Division of application No. 29/803,522, filed on Aug. 13, 2021, now Pat. No. Des. 950,409, which is a division of application No. 29/766,047, filed on Jan. 13, 2021, now Pat. No. Des. 928,020, which is a division of application No. 29/746,551, filed on Aug. 14, 2020, now Pat. No. Des. 928,019.
